FOLDABLE CONTAINER

Stetson Avery, Holliston, and Chauncey A. Hall
Melrose, Mass., assignors to **La Touraine Coffee Co., Boston, Mass., a corporation of Massachusetts**

Application November 19, 1940 Serial No. 366,252

4 Claims. (Cl. 229—62)

Our present invention relates to open mouthed containers of paper or like foldable stock and more particularly to the sealing of such containers to protect their contents against deterioration and to ensure that they may be readily opened without loss.

While our invention may be used in packaging many products, its novel features and advantages may be well illustrated by considering problems attendant the packaging of coffee in such containers as paper bags, envelopes, and the like. After such packages have been filled with a predetermined weight of coffee, they are tightly closed. One of the common objections to sealing the walls together by an adhesive is that coffee particles become lodged adjacent the seal and when the container is opened, generally by tearing the walls below the seal, a considerable quantity of coffee is spilled.

Our present invention has for its purpose the making of such otherwise acceptable containers satisfactory in use. We accomplish this result by providing a tight seal protecting the contents and having the dual advantage of being easily opened while preventing the waste of the contents of the package.

We accomplish this result, in accordance with our invention, by utilizing a container having foldable walls, one of which is longer than the other by reason of a tab or tab portion. The walls are then folded adjacent the mouth and the tab or tab portion is folded against the folded-over part of the other wall to which it is united by adhesive to seal the container with the tab end disposed for engagement so that it may be pulled to release the seal to open the container.

In the accompanying drawing, we have illustrated an embodiment of our invention to illustrate its novel features and advantages. In the drawing:

Fig. 1 is a fragmentary front view of a typical package.

Fig. 2 is a view similar to Fig. 1 but showing the package closed in accordance with our invention.

Fig. 3 is a fragmentary enlarged vertical section along the lines 3-3, of Fig. 2, and

Fig. 4 is a similar section along the lines 4—4, of Fig. 1.

We have shown in the drawing, as indicative of the type of container or package with which we are concerned, an open mouth bag or envelope B of paper or like foldable stock having a front wall 1 and a back wall 2. The back wall 2 conventionally includes a tab portion 3, generally ta-

PATENT OFFICE

pered as shown, and is accordingly of greater length than the wall 1. The edge of the wall 1 and of the tab portion 3 is generally formed with serrations 4.

In accordance with the embodiment of our invention shown in the drawing, after the package B is filled with a predetermined weight of coffee, for example, the walls 1 and 2 are folded adjacent the mouth of the container along a transverse line indicated at 5 to bring the over-folded part 1^a of the shorter wall 1 in a position to partially overlie the over-folded part 2^a of the longer wall 2. As shown in Fig. 3, this fold closes the upper part of the container sufficiently to prevent coffee particles from working into a position where they would be spilled when the seal was broken.

The over-folded part 2^a of the wall 2 is then folded transversely preferably adjacent the base of the tab portion 3, against the over-folded portion 1^a of the shorter wall 1 to which it is sealed in any desired way. For purposes of illustrating a suitable seal, we have indicated in Fig. 1 a coating of suitable adhesive carried by the tab portion 3 and that portion of the wall 1 that constitutes the over-folded part 1^a to ensure their registry. Preferably the coatings 6 terminate well inwardly of the sides of the wall 1 and the tab portion 3 to minimize the possibility of tearing the paper when the containers are opened. It is desirable, however, that the adhesive be "light" by which term we mean that while it must tightly seal the mouth of the container, it must yield readily to avoid tearing the stock from which the container is made. The use of a light seal is possible because the first fold effectively prevents coffee or like particles from working into the over-folded part and the pressure of the contents is not exerted against the seal.

In accordance with our invention, the tab 3 extends beyond the end of the package established by the first fold, to be readily engageable when the container is to be opened. When the tab 3 is pulled, the seal between the tab 3 and the over-folded part 1^a is cleanly broken as the parts 1^a and 2^a are unfolded as shown by a comparison of Figs. 3 and 4.

We are thus able to provide, in accordance with our invention, in a container of low cost, a tight seal that may be easily broken without loss 50 of the contents.

What we therefore claim and desire to secure by Letters Patent is:

front wall and constituting a tab, the said front and rear walls being folded together rearwardly and downwardly along a line below the upper edge of the front wall to close the mouth of the bag, the said tab being folded upwardly against the rearwardly and downwardly folded portion of the front wall, and fastening means uniting said tab with the rearwardly and downwardly folded portion of said front wall to maintain the mouth of the package closed, said tab projecting above said fold line to be gripped and pulled to release said fastening means and to open the mouth of the package.

2. A package as set forth in claim 1 in which the fastening means uniting the tab with the rearwardly and downwardly folded portion of the front wall comprises an adhesive extending transversely of said walls but spaced inwardly of the edges thereof.

3. A package of the bag type comprising a bag having front and rear walls, the top portion of one wall extending beyond the top of the other wall and constituting a tab, said walls being folded together downwardly with the shorter wall on the outer side of the fold along a line below the upper edge of the shorter wall to close the mouth of the bag, the longer wall being upwardly folded

against the downwardly folded part of the shorter wall, and means securing the upwardly folded longer wall to the face of the downwardly folded part of the shorter wall to maintain the mouth of the bag closed, and the top edge of the tab being exposed to be gripped and pulled to release the seal and to open the mouth of the package.

4. A package of the bag type comprising a bag having front and rear walls, the top portion of one wall extending beyond the top of the other wall and constituting a tab, fastening means comprising a coating of adhesive on the inner surface of the tab a substantial distance below its top and on the outer surface of the shorter wall, said walls being folded together downwardly with the shorter wall on the outer side of the fold along a line below the upper edge of the shorter wall to close the mouth of the bag, the longer wall being upwardly folded to bring its coating of adhesive against the coating of adhesive on the shorter wall thereby to establish a seal between the walls to maintain the mouth of the bag closed, and the top edge of the tab being exposed to be gripped and pulled to release the seal and to open the mouth of the package.
